US0D1003214S

(12) **United States Design Patent** (10) Patent No.: **US D1,003,214 S**
(45) Date of Patent: ** Oct. 31, 2023

(54) **QUADCOPTER**

(71) Applicant: **AMAX GROUP USA, LLC**, Bellaire, TX (US)

(72) Inventor: **Darren Scott Matloff**, Los Angeles, CA (US)

(73) Assignee: **AMAX GROUP USA, LLC**, Houston, TX (US)

(**) Term: **15 Years**

(21) Appl. No.: **29/787,937**

(22) Filed: **Jun. 9, 2021**

(51) LOC (14) Cl. **12-07**

(52) U.S. Cl.

USPC **D12/328**

(58) **Field of Classification Search**

CLAIM

The ornamental design for a quadcopter, as shown and described.

DESCRIPTION

FIG. 1 is a back, top, and right side perspective view of a quadcopter embodying my new design, with arms shown in an opened configuration.

FIG. 2 is a back view thereof.

FIG. 3 is a front view thereof.

FIG. 4 is a right side view thereof.

FIG. 5 is a left side view thereof.

FIG. 6 is a top view thereof.

FIG. 7 is a bottom view thereof.

FIG. 8 is a front, top, and left side perspective view of the quadcopter of FIG. 1, with the arms shown in a closed configuration.

FIG. 9 is a back view thereof.

FIG. 10 is a front view thereof.

FIG. 11 is a right side view thereof.

FIG. 12 is a left side view thereof.

FIG. 13 is a top view thereof; and,

FIG. 14 is a bottom view thereof.

Broken lines, where shown, illustrate portions of the quadcopter that form no part of the claimed design.
